LUGGAGE HANDLE OR SIMILAR ARTICLE

Leon Lautin, 43 White Drive N.,
Cedarhurst, N.Y. 11516

Filed Nov. 19, 1968, Ser. No. 14,531

Term of patent 14 years

Int. Cl. D8—03
U.S. Cl. D8—154

FIG. 1

FIG. 2

FIG. 3

FIG. 4

FIG. 5

FIG. 6

FIG. 7

FIG. 1 is a perspective view of a luggage handle or similar article showing my new design;

FIG. 2 is a top plan view;

FIG. 3 is a front elevational view;

FIG. 4 is a side elevational view;

FIG. 5 is a section taken along lines 5—5 of FIG. 3;

FIG. 6 is a section taken along lines 6—6 of FIG. 3;

and

FIG. 7 is a section taken along lines 7—7 of FIG. 3.

The characteristic feature resides in the particular inner and outer corner relationships as shown.

I claim:

The ornamental design for a luggage handle or similar article, substantially as shown and described.
